(57) **CLAIM**

The ornamental design for an electric mixer, as shown and
described.

DESCRIPTION

FIG. 1 is a perspective view of an electric mixer according
to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part
of the claimed design.

Stipple-filled areas represent areas with a matte surface
finish.

(Continued)

Diagonal shading is used to represent areas with reflective surface finish.

1 Claim, 7 Drawing Sheets

Related U.S. Application Data

continuation of application No. 29/682,091, filed on Mar. 1, 2019, now Pat. No. Des. 892,539.
